DESK TELEPHONE SET

Herbert F. Obergfell, deceased, late of River Forest, Ill., by Amanda Obergfell, executrix, River Forest, Ill., assignor to Automatic Electric Laboratories, Inc., Chicago, Ill., a corporation of Delaware

Application March 25, 1944, Serial No. 528,034

7 Claims. (Cl. 179—146)

The invention relates in general to telephone sets, but more particularly to an improved desk telephone of the cradle type.

The object of the invention is to improve the construction of the desk telephone, fingers lifting device shown and claimed in Patent 2,200,810, issued May 14, 1940, to Hans Sengebusch.

In practice it was found that the fingers lifting bail, shown in the above mentioned Sengebusch patent, would on certain occasions, when the desk telephone was being moved from place to place by the fingers lifting bail, disengage itself from its pivotal mountings in the mounting blocks with the result that the entire desk telephone would fall to the floor. This defect was due to the inherent construction of the fingers lifting bail, the arms of which were sufficiently flexible to permit the pivot pins to be withdrawn from the pivot holes in the mounting blocks when sufficient pressure was applied to the sides of the bail arms. The main object of the present invention is to overcome this defect by providing a tongue and groove interlocking arrangement between the mounting blocks and the arms of the bail so that after the bail is rotated to its lifting position it is impossible for the arms to be disengaged from their mounting blocks.

Other objects and features of the invention will be apparent from the detailed description of the drawing comprising Figs. 1 to 9, inclusive.

Fig. 1 shows a perspective view of the desk telephone with the hand telephone removed from the cradle.

Fig. 2 shows a front view of the fingers lifting bail.

Fig. 3 shows a cross section of the fingers lifting bail taken on the line A—A of Fig. 2.

Fig. 4 shows an enlarged cross section of one of the arms taken on the line B—B of Fig. 3.

Figs. 5 to 8, inclusive, show different views of one of the mounting blocks.

Fig. 9 shows an assembly drawing of one of the mounting blocks and one of the arms of the bail in normal position. The dotted lines indicate fully operated position of this arm.

Referring now in general to the drawing the casing 10 of the desk telephone is formed in one piece of some suitable plastic insulating compound and has a general shape roughly corresponding to a truncated pyramid thereby enabling ease in moulding. The base portion of the casing comprises ten sides or skirts 11 which extend substantially vertical for a short distance at which point the front, rear, and side surfaces

slope inwardly. The two side surfaces 12 and 13 slope upwardly and inwardly from the skirt side-portion only a short distance at which point both the side surfaces extend substantially vertical. The front surface 14 slopes upwardly and inwardly at an angle of substantially 40 degrees until it is rounded in a substantially horizontal top portion 15 which extends a short distance to the rear where it merges into the rear surface 16. The rear surface 16, extends from the rear skirts 11 to where it merges with the top portion 15, slopes upwardly and inwardly. The slope of the rear surface 16 is a perfect arc of a circle having substantially a nine inch radius. The two side surfaces form side walls 17 and 18 which extend from the top portion 15 near the front to the rear skirts 11, thereby forming a channel comprising the two inside surfaces 19 and 20 of the side walls and the curved rear surface 16. Each side wall at its highest point terminates in a pair of spaced pillars 21. The space between these pillars forming a cradle for the well-known combination transmitter and receiver handset.

A plunger 22 is movably mounted in the space between the two pillars in each side wall. These plungers are provided for operating the switchhook springs (not shown) whenever the handset is removed or replaced on the cradle.

A base plate 23 having a rubber ring 24 is secured to the bottom of the cover by means of screws which screw into threaded inserts in the cover.

The channel formed by the curved rear surface 16 and the inside surfaces 19 and 20 of the two side walls 17 and 18 starts at the rear and gradually deepens. Its greatest depth being at a vertical point from the two rear pillars 21 in the side walls. Due to the depth of the channel the fingers can firmly grasp the underside of a handset (not shown) resting on the plungers 22 in the cradle between the pillars 21 and side walls 17 and 18. In known desk sets only the tip ends of the fingers can grasp the sides of the handset resulting in an insecure finger grip on the handset. This insecure finger grip often permits the handset to fall after it has been removed from the cradle. In case the handset slips and falls from the insecure finger tip grip considerable damage or breakage may occur.

Another advantage provided by this channel is to minimize cord interference. For example, a subscriber, in hurriedly replacing the handset on the cradle, may allow the cord extending from the desk stand to the handset, to loop between the plungers of the cradle. In many instances

these loops prevent the proper depression of the plungers since the handset rests on the cord and does not depress the plungers sufficient to properly control the substation circuit. Under these conditions the telephone is temporarily out of service in regard to incoming calls. This defect has been overcome by providing a channel which starts near the front pillars and which has sufficient depth so that the cord will not interfere with the proper operation of the plungers in case the cord is accidentally looped in between the pillars.

Mounting blocks 32 are provided between each pair of pillars 21 in the side walls 17 and 18. These mounting blocks 32 form the top surface 15 of the cradle which supports the hand telephone and are provided with threaded screw holes 36 into which screws from inside the casing hold the mounting block in place. A hole 37 is provided in each mounting block 32 for the plungers 22 which operate the cradle switchhook springs (not shown). A hole 35 is also provided in each mounting block 32 for pivotally mounting the fingers lifting bail 50.

Due to the general shape of the cover or casing 10 which is provided with smooth sloping sides, the desk telephone is not easily picked up and moved by hand from place to place because no suitable finger or hand grip is available for lifting and moving the desk telephone. In order to provide means for easily lifting and moving the desk telephone from place to place a fingers lifting bail 50 has been provided. The lifting bail is in general U-shaped having a pair of arms 52, the outer extremities of which are provided with pivot pins 51 which are insertable in the holes 35 of the mounting blocks 32 for the purpose of rotating the closed end of the lifting bail above the hand telephone. It will be noticed that each of the arms has a hook-shaped curvature near its outer extremities and that a thin plate, web, or tongue 53 is located within this hook-shaped curvature of the arms. A shoulder portion 54 of the arms is shown adjacent the web 53.

An overhanging projection stop 61 and a groove, or slot 60 are shown on each of the mounting blocks 32. Both the slot 60 and the projection stop 61 are located in the path of rotation of the arms 52. Normally the bail rests on the sloping surface 16, as shown in Fig. 1, and by pressing inwardly on each of the arms 52 it is possible to remove the bail by removing the pins 51 from the hearing holes 35. When the bail is to be used for moving the entire desk telephone the user grasps the closed portion of bail 50 and rotates the same in an upward direction. During this manual rotation the web, or tongue 53, enters the slot 60 in the block 32 to prevent sideways movement of the arms thereby interlocking the bail and mounting blocks. The rotation of the bail in the upward direction is continued until the shoulder portion 54 of the arms engages the projection stop 61 thereby limiting the rotation of the bail, at a predetermined point. During the time the desk telephone is carried from one place to another by means of the bail the web 53 and slot 60 form a tongue and groove locking arrangement for preventing the disengagement of the arms from the mounting blocks.

Having described the invention, what is considered to be novel is pointed out in the appended claims.

What is claimed is:

1. In a desk telephone, a casing having spaced pillars forming the hand telephone cradle sup-

ports, a pair of mounting blocks positioned between said pillars forming the base portion of the cradle supports, a fingers lifting bail having a pair of arms rotatably mounted in said blocks, each end of said arms having a hook-shaped curvature, a projection on each of said blocks forming a slot located in the path of rotation of said arms, and a web located within each of said hook-shaped curvatures of said arms rotated in said formed slots between said projections and the main body portion of said blocks in response to the manual rotation of said bail for locking said bail to said blocks to prevent removal of said bail from said blocks.

2. In a desk telephone, a casing having side walls, a pair of spaced pillars terminating the upper extremities of each side wall and forming the cradle support for the hand telephone, a mounting block positioned between each pair of pillars forming the base portion of the cradle support, a plunger in each side wall extending through said blocks between said pillars, said plungers operable in response to the removal and replacement of said hand telephone with respect to the cradle support, a fingers lifting bail having a pair of arms pivotally mounted in said blocks, an overhanging projection on each of said blocks forming a slot and a stop located in the path of rotation of said arms, a web located near the outer extremities of said arms rotated in said formed slots between the overhanging projection stops and the main portion of said blocks in response to the manual rotation of said bail for interlocking said bail and blocks to prevent removal of said bail from said blocks, and a portion of each of said arms engaging said overhanging projection stops to limit the manual rotation of said bail.

3. In a desk telephone, a casing having spaced pillars forming the hand telephone cradle supports, a pair of mounting blocks positioned between said pillars forming the base portion of the cradle supports, a fingers lifting bail having a pair of arms rotatably mounted in said blocks, each end of said arms having a hook-shaped curvature, an overhanging projection on each of said blocks forming a slot and a stop located in the path of rotation of said arms, a web located within each of said hook-shaped curvatures of said arms rotated in said formed slots between the overhanging projection stops and the main body portion of said blocks in response to the manual rotation of said bail for interlocking said bail and blocks to prevent removal of said bail from said blocks, and a shoulder portion on each of said arms adjacent said webs engaging said overhanging projection stops to limit the manual rotation of said bail.

4. In a desk telephone having spaced pillars forming the hand telephone cradle supports, a pair of mounting blocks positioned between said pillars, a fingers lifting bail having a pair of arms pivotally mounted in said mounting blocks, an overhanging slot in said blocks located in the path of rotation of the arms of said bail, and a web on the arms of said bail entering said slots in response to the rotation of said bail for interlocking said bail and said blocks to prevent dis-placement of said bail from said blocks.

5. In a desk telephone, a casing having side walls, a pair of spaced pillars terminating the upper extremities of each side wall, a mounting block positioned between each pair of pillars, a fingers lifting bail having a pair of arms, a pin on the outer extremities of said arms for pivotally mounting said arms in said blocks, an

overhanging projection on each of said blocks forming a slot and a stop located in the path of rotation of the arms of said bail, a web located near the outer extremities of said arms rotated in said formed slots between the overhanging projection stops and the main portion of said blocks in response to the manual rotation of said bail for interlocking said bail and blocks to prevent removal of said bail from said blocks, and a portion of each of said arms engaging said overhanging projection stops to limit the manual rotation of said bail.

6. In a desk telephone, a casing having spaced pillars forming the hand telephone cradle supports, a pair of mounting blocks positioned between said pillars forming the base portion of the cradle supports, a fingers lifting bail having a pair of arms pivotally mounted in said blocks, and a tongue and groove locking means on said

arms and blocks effective for preventing removal of said bail from said blocks in response to the manual rotation of said bail.

7. In a desk telephone, a casing having spaced 5 pillars forming the hand telephone cradle supports, a pair of mounting blocks positioned between said pillars forming the base portion of the cradle supports, a fingers lifting bail having a pair of arms pivotally mounted in said blocks, said arms being sufficiently resilient to permit removal of said bail from said mounting blocks, and a tongue and groove locking means on said arms and blocks effective for preventing removal of said bail from said blocks in response to the manual rotation of said bail.
